PERMUTATION LOCK

Maurice Zuili, Paris, France

Application June 21, 1932, Serial No. 618,513. In
Great Britain and France April 16, 1932

11 Claims. (Cl. 70—54)

The present invention relates to permutation locks and has for its primary object to provide a lock of this kind constituting an improved structure with respect to the permutation lock described in my co-pending application No. 510-822, filed Jan. 23, 1931 the improvements mainly consisting in a device incorporated in the lock mechanism for automatically returning the buttons to aligned position as soon as the stud-catches have been disengaged from the lock casing and thus for preventing any person not conversant with the combination from discovering or guessing it from the location of certain buttons when the lock is in the open position.

15 A further object of the invention is to provide a permutation lock as aforesaid wherein the stud-catches engaging through the lock casing are rigidly fitted upon a cover or hood matching the shape or outline of said casing, the 20 one part of the article to be locked, for instance the body of a portfolio or satchel, being permanently secured to the lock casing or to the cover whereas the other part of said article, for instance the flap of the portfolio or satchel, is 25 permanently secured to the cover or to the casing of the lock, whereby when said casing and cover are locked in close superimposed relation the two parts of the article in question are locked closely adjacent to each other and access can 30 not be had into the article, which precludes pilfering or other tampering of its contents.

A still further object of the invention is to provide a permutation lock as aforesaid wherein the mutual engagement of the locking members: 35 bolts and keeper apertures which are specifically in the form of button extensions and of indentations or notches respectively, said notches being formed in a tumbler plate or locking plate, is adapted to prevent any person not conversant 40 with the combination of the lock from picking the buttons for haphazard discovering the secret of the lock i.e. finding the particular buttons which require to be displaced in their slots for opening the lock and severing the two parts of 45 the article, such for instance as a portfolio or satchel.

Still a further object of the invention is to provide a permutation lock as aforesaid wherein the arrangement of its internal parts with respect to the buttons and stud-catches is adapted 50 to prevent any person not conversant with the combination who tries to pick the lock from discovering the particular buttons which require to be displaced for normally opening it by tactually feeling differences in the resistances offered

to displacement by said buttons when the cover is being pulled from the lock casing, said arrangement of parts having the effect of rendering said resistances uniform for all the buttons regardless of their location.

Still a further object of the invention is to provide a permutation lock as aforesaid of simple and rugged construction, made up of a minimum number of parts capable of being made of stamped or punched steel sheets and readily assembled with limited cost and labor, said lock being compact and self-contained and therefore of smart appearance.

With these and such other objects in view as will incidentally appear hereinafter, the invention comprises more specifically the novel construction and arrangement of parts that will now be described in detail with reference to the accompanying diagrammatic drawings forming a part of the present disclosure and showing a permutation lock exemplifying the invention.

In the drawings:

Figure 1 is a front elevational view of the lock, the left hand side of this view being taken, assuming the cover to be applied over the lock casing in closed position, whereas the right hand side of this view is taken, assuming the cover to have been omitted.

Figure 2 is an edge view, partly in section, showing on the left hand side, the lock casing riveted to a part of the article to be locked, designated by A, and on the right hand side the cover riveted to the companion part of the article designated by B, and carrying the stud-catches.

Figure 3 is an inverted plan view of the lock casing, assuming the base plate to be omitted and the tumbler plate to be partly broken away for the sake of clearer illustration, four buttons only being shown, these buttons being adjusted in different positions.

Figure 4 is a sectional view on the line IV—IV (Fig. 3).

Figure 5 is a sectional view on the line V—V (Fig. 3) the arrow showing the direction of displacement of the buttons.

Figure 6 is a sectional view on the line VI—VI (Fig. 3).

Figure 7 is a sectional view on the line VII—VII (Fig. 3).

Figure 8 is a fragmentary front view of the flanged lock casing, the dotted lines showing the indented plate which can be shifted longitudinally for changing the combination of the

lock by permuting or changing the key buttons, the teeth between the indentations being shown in the position which they occupy for retaining the buttons in the casing.

5 Figure 9 is a view similar to Figure 8 but assuming the indents of the indented permutation plate to occupy the position for freeing the buttons from the casing.

10 Figures 10, 11 and 12 are fragmentary views illustrating in a very diagrammatic way the co-operation of the cam surfaces on the stud-catches and spring-influenced indented tumbler plate.

15 Figure 13 is a plan view of the base plate pivotally carrying a spring-rocked shutter and having abutments for the springs that influence the tumbler plate.

20 Figure 14 is a sectional view on the line XIV—XIV (Fig. 13), the upper arrow showing the direction in which the shutter is rocked by its spring while the lower arrow shows the direction in which it is rocked back against the action of said spring by the co-operating cam surfaces on the stud-catches.

25 Figure 15 is a fragmentary edge view showing on an enlarged scale the engagement of the shutter against the longer lug of a button represented in dot-and-dash lines before said shutter has been rocked off by the stud-catch.

30 Figure 16 is a fragmentary view similar to Figure 15 but showing the shutter rocked off said button lug by the action of the stud-catch.

35 Figure 17 is a transverse sectional view drawn on the same scale as Figures 15 and 16 of the lock casing, showing the yieldingly-supported buttons and a slightly modified arrangement of parts adapted to prevent the lock combination from being surreptitiously discovered by displacing the buttons one after the other while pulling the cover off the casing.

40 Figure 18 is a fragmentary sectional view of the lock represented in Figure 17, showing the stud-catch fully driven home, the cam surface on said stud-catch being clear of the tumbler plate.

45 Figure 19 is a view similar to Figure 18 showing the stud-catch slightly disengaged from the lock casing as its cam surface reaches the tumbler plate, the cover being slightly spaced from the lock casing.

50 Like reference numerals and characters designate like parts throughout the several views of the drawings.

55 As illustrated, the lock casing 1 of elongated trough-like shape has a peripheral flange 2 by means of which it may be permanently secured by rivets 3 or otherwise to one of the two parts of the article to be locked, for example to the body A of a portfolio or satchel. The lock casing 1 is formed in one of its walls with a series of parallel equally-sized aligned slots 4.

60 A cover 5 having a peripheral flange 6 is permanently secured to the other part of the article to be locked, for example to the flap B of the portfolio or satchel by means of rivets 7 or otherwise. The cover 5 is so sized and shaped as to fit over the casing 1 in close superimposition, and it is formed in its bottom wall with a series of slots 8 which correspond in size and location to the slots 4 so that when the casing 1 and cover 5 are superimposed the slots 4 and 8 register.

65 The slots 4 and 8 are therefore in equal number, preferably eight to ten for accommodating a similar number of buttons and allowing of a

70 larger number of locking combinations as will be described hereafter.

75 Within each slot 4 of the casing 1 is accommodated a button or knob 9 having a reduced neck so sized as to be displaceable in the slot in a plane substantially at right angles to the longitudinal axis of said casing. The head of each button 9 protrudes out of the casing 1 beyond the slot 4 and is advantageously knurled or otherwise roughened for permitting an easier grip, and the heads of all the buttons 9 are equally-sized and of similar appearance.

80 The portion of each button 9 which extends into the casing 1 is formed (see Fig. 17) with a pair of symmetrical side ears 10, 11 and with a pair of lugs 12, 13 extending at right angles to said ears, these lugs being of unequal length, the longer lug 12 being adapted to form a locking bolt as will appear hereafter. The lugs 12, 13 are separated from one another by a clearance 95 14.

85 Inside the lock casing 1 and adjacent its slotted wall is located a plate 15 having a length slightly less than the internal length of the casing to be longitudinally shiftable therein. This plate 15 has a central aperture 16 (see Figs. 8 and 9) each of the longitudinal edges of which is indented. The indentations or notches 17 on one side of the aperture 16 are advantageously deeper than the indentations or notches 18 on its other side. The widths of the indentations 17, 18 and intermediate teeth 19, 20 are so reckoned that when the plate 15 is at one end of its longitudinal stroke (see Fig. 8) the slots 4 coincide with the teeth 19, 20 whereas when the plate 15 100 is at the other end of its stroke (Fig. 9) the slots 4 coincide with the indentations 17, 18.

90 It will thus be seen that the indented plate 15 holds the buttons 9 engaged by their side ears 10, 11 in the casing 1 when the teeth 19, 20 register with said ears whereas the indented plate 15 frees the buttons 9 from the casing 1 when the indentations 17, 18 register with the ears 10, 11.

95 Thus by simply shifting the plate 15 longitudinally from an end position to the opposite end position, the buttons 9 may be disengaged from the lock casing 1 or held engaged therein securely. For permitting to shift the plate 15 for this purpose, the lock casing 1 has an elongated hole 115 21 and the plate 15 a registering smaller hole 22, whereby by inserting a nail or other sharp tool (not shown) into the holes 21, 22, the plate 15 may be shifted from the position shown in Figure 8 to the position shown in Figure 9 or 120 vice versa. This shifting motion of the plate 15 is only permissible when the lock is opened i. e. when the cover 5 is separated from the casing 1 since no hole similar to the hole 21 is formed in said cover. This prevents any tampering of the 125 lock when it is in closed position.

130 Adjacent the permutation plate 15 is positioned a permutation plate 23 so sized as to fit into the casing 1 and provided with a central aperture 24 the side edges of which have indentations 25 forming guides for the button lugs 12, 13 to prevent sidewise collapsing of said lugs upon movement thereof in slots 4.

135 The permutation plate 15 and the guiding plate 23 may be formed as shown in Figs. 4-7 140 so as to contact with each other. Preferably however they are formed as shown on a larger scale in Fig. 17, the plate 15 having downwardly extending side flanges 15a terminating at a short distance from the edges of the plate 23, the 145

said edges contacting with the side walls of the casing 1. The purpose of the clearance left between the flanges 15^a on the plate 15 and the plate 23 will be described hereafter.

5 Against that face of the crenellated plate 23 opposite to the face directed towards the permutation plate 15 rests a tumbler plate 26 formed with a central aperture 27, end apertures 28 separated from the aperture 27 by cross bars 29 adapted to act as cam surfaces as will be hereinafter described. The longitudinal edges of the aperture 27 is formed with notches 30 which differ in depth from one edge to the other. The notches 30 are spaced to an extent corresponding to the distance between the buttons 9 and are adapted to form keepers for their bolt-like lugs 12, as will be described hereafter. The length of the tumbler plate 26 is so reckoned as to permit it to move longitudinally in the 10 casing 1. The shape of the keeper notches 30 is preferably trapezoidal as shown in Fig. 3.

The tumbler plate 26 is held in the casing 1 by a flanged base plate 31 fitted into the open end of said casing. This base plate (see Fig. 13) is punched or stamped to form holes 32 and bearings 33 for a pivot spindle 34 which carries an elongated shutter 35 the length of which approximates the distance from the first button to the last button of the row of buttons 9. This 15 shutter 35 is influenced permanently by a primary spring 37 coiled around the spindle 34 and is provided with end cam surfaces 36 of arcuate shape. The width or height of the shutter 35 is such as to enable it to permanently project 20 into the clearance 14 between the button lugs 12, 13 for a purpose that will appear hereafter.

Coil springs 38 forming secondary spring means are fastened to the base plate 31 and to the tumbler plate 26, the latter is supported 25 solely by said springs, which gives its longitudinal displacements in the lock casing 1 a certain amount of resiliency, as shown by the dot-and-dash line in Figure 11.

The cover 5 is fitted on its face engaging the 30 slotted face of the casing 1 and on both ends of the row of slots 8 with a stud-catch 39 the free end of which is formed with a coned protuberance 40 adapted to act as a cam surface and to co-operate with cam surfaces on the tumbler plate 26 and with the cam surfaces 36 of the shutter or rocker 35. To that effect, the 35 length of the stud-catches 39 is so reckoned that when the cover 5 fits over the casing 1 and said catches engage through ports 41 formed in the slotted wall of said casing, the coned cam surfaces 40 occupy a position beyond the tumbler plate 26 or in other words in the clearance left 40 between said plate 26 and the base plate 31.

Straddling the portion of each button 9 which 45 projects into the lock casing 1 is a V-shaped or bridge-like blade spring 42 so cut out as to accommodate the side ears 10, 11 of the button and resting by the ends of its diverging legs on the guiding plate 23. The springs 42 prevent 50 accidental shifting of the buttons 9 and incidentally hold the side ears 10, 11 in contact with plate 15.

The operation of the improved permutation lock is as follows:

55 Assuming the lock to be in closed position that is to say assuming the cover 5 to be fitted over the casing 1 which means that the buttons 9 project out of the slots 8, it will be understood that the stud-catches 39 which then engage through the ports 41 of the casing 1 occupy the

position shown in Figure 18, their coned cam surfaces 40 being situated beyond the tumbler plate 26. These cam surfaces 40 then engage the co-operating cam surfaces 36 of the shutter 35 and thus hold the latter in the position shown

80

in Figure 16 against the action of the spring 37 coiled around the pivot spindle 34. As a result of this, the free longitudinal edge of the shutter 35 allows the buttons 9 to be freely displaced along the slots 4, 8. This permits the user to

85

displace the particular buttons which have been previously adjusted to form the combination of the lock or in other terms those buttons whose lug or bolt 12 engages a keeper notch 30 in the tumbler plate 26 when said buttons are aligned

90

relative to the remaining buttons. One or several buttons may have been adjusted in that way before-hand depending on the combination to be obtained. When thus the adjusted buttons

95

9 have been displaced along the respective slots that is to say disaligned, their lugs or bolts 12 have freed the corresponding keeper notches 30 in the tumbler plate. If now the cover 5 is pulled off the casing 1, the cam surfaces 40 on the stud-catches 39 engage the cross bars 29 of

100

the tumbler plate 26 against the action of the springs 38 and shift said plate momentarily as shown by the upper arrow in Figure 3. Thus the stud-catches 39 can be disengaged from the casing 1 and the part B of the article can be 105 severed from the companion part A. Immediately after, the tumbler plate 26 is returned to locking position by its springs 38 as shown by the lower arrow in Figure 3.

However, as soon as the stud-catches 39 have 110 been withdrawn from the casing 1 as above-described, their cam surfaces no longer hold the shutter 35 whereby the latter rocks back under the action of its spring 37 and engages the button lugs, which automatically aligns all buttons 115 9. This means that as soon as the lock is opened, all buttons, whether adjusted to build the combination or not, are automatically re-aligned. The instantaneous resumption of the button alignment makes it impossible for anyone not 120 conversant with the combination to guess the latter by an inspection of the buttons.

When now the lock has to be brought back to closed position by fitting the cover 5 over the casing 1 and thrusting the stud-catches through 125 the ports 41, the tumbler plate 26 although locked by its springs 38 can yield downwardly and rearwardly to a slight extent into the clearance between it and the base plate 31. This yielding motion is clearly illustrated by the arrows in Figures 10, 11, 12 which show the co-operation of the coned cam surfaces 40 on the stud-catches 39 and the cross bars 29 on the tumbler plate 26 elastically supported by the springs 38. Once the stud-catches 39 are fully 130 driven into the casing, the lock is invariably closed and can not be re-opened except by disaligning the proper buttons as above stated.

Assuming now wrong buttons or "dummy" buttons to be displaced along the slots 4, 8, it 135 will be understood that this will bring the corresponding bolts or lugs 12 into more keeper notches 30 of the tumbler plate 26 and will render the opening of the lock impossible even if the proper buttons are afterwards disaligned. 140 Thus disalignment of more buttons than is necessary for opening the lock has the result of additionally locking it and of still further puzzling the person who endeavors to tamper with or pick it.

150

For changing the combination of the lock or in other words for altering those buttons whose bolts 12 engage keeper notches 30 of the tumbler plate 26 when said buttons are aligned relative to the remaining buttons, all that is necessary, after having opened the lock as aforesaid is to insert a nail or other sharp tool (not shown) into the coincident holes 21, 22 in order to shift the permutation plate 15 for freeing the button ears 10, 11. The buttons 9 can then be extracted from the casing 1 and adjusted by a rotation of 180° upon themselves. It is thus possible to change the buttons whose bolts 12 engage keeper notches 30 of the tumbler plate 26 when said buttons are aligned. To lock back the ears of the buttons, after this new adjustment, all that is necessary is to shift back the permutation plate 15 into a position for which its teeth 19, 20 engage the button ears 10, 11.

Should a person not conversant with the combination of the lock that is to say not knowing which are the buttons to be displaced in the slots 4, 8 in order to separate the cover 5 from the casing 1 endeavor to pick the lock by displacing the buttons 9 haphazard while exerting a fractional stress on the cover 5 with respect to the casing 1 held stationary, it will be understood from Figure 19 that this endeavor will cause the guiding plate 23 to press uniformly on all button ears 10, 11 against the action of the V-shaped blade springs 42. As a result of this, the person in question will not be given tactually any clue to the particular buttons which require to be displaced to open the lock.

Additional security against such an endeavor to tamper with or pick the lock is also given by shaping the keeper notches 30 of the tumbler plate 26 trapezoidally as shown in Fig. 3. As will be understood, the bolts 12 of the buttons 9 only engage with the edge of the keeper notches by one sharp edge so that their displacement is quite easy and there is no risk of a slight longitudinal motion of the tumbler plate 26 under the traction of the stud-catches 39 by an unauthorized person interfering with the proper displacement of the bolts 12 of the adjusted buttons. Thus the person trying to tamper with the lock can not obtain information in that way as regards the right buttons which require to be operated to open the lock.

It will be appreciated that the improved permutation lock as above described can be applied for miscellaneous uses, wherever two parts or members require to be securely locked together without a key.

Numerous minor constructional details of the lock might be altered without departing from the spirit of the invention and the scope of the subjoined claims.

What I claim and desire to secure by Letters Patent is:

1. A permutation lock comprising a casing having aligned slots, buttons movable along the respective slots, each button projecting out of the casing and having an inner bolt offset from its centre, adjustable means maintaining the buttons engaged in the casing in one position and releasing them in another position so as to permit selected buttons to be extracted and re-inserted into the casing after a rotation of 180° for changing the relative positions of their bolts to form a new combination, and a tumbler plate in the casing co-operating with the button bolts.

2. A permutation lock comprising a casing having parallel rectangular aligned slots, buttons movably fitted in the respective slots, each button having a head projecting out of the casing, symmetrical ears and a bolt offset from its centre, the ears and bolt extending into the casing and being co-planer with the head, adjustable means co-operating with the button ears to retain them engaged in the casing in one position and to free them in another position so as to permit selected buttons to be extracted from and re-inserted into the casing after a rotation of 180° for changing the relative positions of their bolts to form a new combination, and a tumbler plate in the casing co-operating with the button bolts.

3. A permutation lock comprising a ported casing having aligned slots, buttons movable along the respective slots, each button projecting out of the casing, an internal bolt offset on each button from its centre, adjustable means holding the buttons engaged in the casing in one position and releasing them in another position so as to permit selected buttons to be extracted from and re-inserted into the casing after a rotation of 180° for changing the relative positions of their bolts to form a new combination, a slotted cover fitting over the casing and having catches insertable through the casing ports, and a spring-urged tumbler plate movable in the casing and co-operating with the bolts for locking said catches.

4. A permutation lock comprising a ported casing having aligned slots, buttons movable along the respective slots, each button having a head projecting out of the casing, symmetrical ears and a tail-like bolt offset from its centre, the ears and bolt of each button extending into the casing and being co-planar with the head, an adjustable indented plate co-operating with the button ears to retain them in the casing in one position and to free them in another position so as to permit selected buttons to be extracted from and re-inserted into the casing after a rotation of 180° upon themselves for changing the relative positions of their bolts to form a new combination, a slotted cover fitting over the casing and having catches insertable into the casing ports, and a spring-urged tumbler plate movable in the casing at an angle to the buttons and co-operating with the bolts for locking said catches.

5. A permutation lock comprising a ported casing having aligned slots, buttons movable along the respective slots, each button projecting out of the casing and having an inner bolt offset from its centre, adjustable means holding the buttons engaged in the casing in one position and releasing them in another position, a slotted cover fitting over the casing and having catches insertable into the casing ports, a spring-urged tumbler plate movable in the casing at an angle to the buttons and engageable by the bolts for locking said catches, and a spring-urged rocker holding the buttons aligned when the catches are released from the tumbler plate and said catches while permitting disalignment of the buttons when the catches are locked by the tumbler plate.

6. A permutation lock comprising a ported casing having aligned slots, movable buttons in the respective slots, each button having a head projecting out of the casing, symmetrical ears and a bolt offset from its centre, the ears and bolt extending into the casing and being co-

- planar with the head, an indented plate adjustable from without the casing and co-operating with the button ears to retain them in one adjusted position and to release them in another 5 adjusted position, a cover fitting over the casing and having slots receiving the button heads, catches on said cover insertable into the ports of the casing, a spring-urged tumbler plate movable in the casing substantially at right angles to the buttons and having on both side edges of a central aperture trapezoidal notches engageable by the bolts for being held thereby and locking said catches, and a plane 10 rocker urged by spring means into the path of the catches for holding the buttons aligned when the catches are freed from the rocker and tumbler plate while permitting selective disalignment of the buttons when the catches are locked by 15 the tumbler plate.
7. A permutation lock comprising a ported casing having aligned slots, buttons movable along the respective slots and having bolts extending into the casing, means for retaining the buttons adjustably in the casing, a cover fitting over the casing and having slots coincident with the buttons, catches on said cover insertable into the ports of the casing, a spring-urged tumbler 20 plate movable in the casing substantially at right angles to the buttons and having on both sides of a central aperture notches engageable by the bolts for locking said catches, and a rocker urged by spring means into the path of the catches 25 for holding the buttons aligned when said catches are released from the tumbler plate and rocker while permitting disalignment of the buttons when the catches engaged said rocker and are locked by said tumbler plate.
- 30 8. A permutation lock comprising a ported casing having aligned slots, buttons movable along the respective slots and having offset bolts extending into the casing, an indented plate adjustable in the casing for retaining or releasing the buttons depending on its adjustment, a cover fitting over the casing and having slots coincident with the buttons, catches on said 35 cover insertable into the ports of the casing, a spring-urged tumbler plate engageable by the bolts to lock said catches, a crenellated plate 40 interposed between the indented plate and tumbler plate for guiding the button bolts, said crenellated plate being thinner than the clearance between the indented plate and the tumbler plate, 45 blade springs resting on the crenellated plate and straddling the respective buttons, and a spring-urged rocker holding the buttons aligned when the catches are released from the rocker and tumbler plate while permitting disalignment 50 of the buttons when the catches engage the tumbler plate and rocker.
- 55 9. A permutation lock comprising a ported casing having aligned slots, buttons movable along the respective slots, each button having a head projecting out of the casing, symmetrical ears and a bolt offset from its centre, the ears and bolt extending into the casing and being co-planar with the head, an indented plate adjustable from without the casing and co-operating 60 with the button ears to retain them in one 65 position of adjustment and to release them in another position of adjustment, a cover fitting over the casing and having slots receiving the button heads, catches on said cover insertable into the ports of the casing, a spring-urged tumbler plate movable in the casing substantially at right angles to the buttons and having on both side edges of a central aperture trapezoidal notches engageable by the bolts for being held thereby and locking said catches, and a plane 70 rocker urged by spring means into the path of the catches for holding the buttons aligned when the catches are freed from the rocker and tumbler plate while permitting selective disalignment of the buttons when the catches are locked by the tumbler plate and rocker.
- 75 10. A permutation lock for locking together a movable part and a stationary part such as the flap and body of a portfolio, comprising a trough-like casing secured peripherally to one of said parts and having one wall formed with ports and with parallel aligned slots, buttons movable along the respective slots and having bolts offset from their centres and extending into the casing, adjustable means holding the buttons engaged in the casing in one adjusted position and releasing them in another adjusted position, a cover secured peripherally to the other of said parts and having slots coincident with the buttons, catches on said cover insertable into the ports of the casing, a spring-urged tumbler plate movable in the casing at an angle to the buttons and engageable by the bolts for locking said catches, and a spring-urged rocker holding the buttons aligned when the catches 80 are released from the rocker and tumbler plate while permitting disalignment of selective buttons when the catches engage the rocker and tumbler plate.
- 85 11. A permutation lock comprising a ported casing having aligned slots, eared buttons movable along the respective slots, each button projecting out of the casing and carrying an inner bolt offset from its centre, an adjustable indented plate holding the buttons engaged in the casing in one adjusted position and releasing them in another adjusted position so as to permit selected buttons to be extracted from and re-inserted into the casing after a rotation of 180° to form a new combination, a slotted 90 cover fitting over the casing and having stud-catches insertable into the casing ports, a spring-urged tumbler plate movable in the casing at an angle to the buttons and having notches engageable by the bolts for locking said catches when 95 all buttons are aligned but disengaged by said bolts when buttons adjusted to form the combination are disaligned, and a spring-urged rocker holding the buttons aligned when the catches are freed from the rocker and tumbler plate while permitting selective disalignment of the buttons when the catches are engaged by the tumbler plate and rocker.
- 100 12. A permutation lock comprising a ported casing having aligned slots, eared buttons movable along the respective slots, each button having a head projecting out of the casing, symmetrical ears and a bolt offset from its centre, the ears and bolt extending into the casing and being co-planar with the head, an indented plate adjustable from without the casing and co-operating with the button ears to retain them in one 105 position of adjustment and to release them in another position of adjustment, a cover fitting over the casing and having slots receiving the button heads, catches on said cover insertable into the ports of the casing, a spring-urged tumbler plate movable in the casing substantially at right angles to the buttons and having on both side edges of a central aperture trapezoidal notches engageable by the bolts for being held thereby and locking said catches, and a plane 110 rocker urged by spring means into the path of the catches for holding the buttons aligned when the catches are freed from the rocker and tumbler plate while permitting selective disalignment of the buttons when the catches engage the rocker and tumbler plate.
- 115 13. A permutation lock comprising a ported casing having aligned slots, eared buttons movable along the respective slots, each button having a head projecting out of the casing, symmetrical ears and a bolt offset from its centre, the ears and bolt extending into the casing and being co-planar with the head, an indented plate adjustable from without the casing and co-operating with the button ears to retain them in one 120 position of adjustment and to release them in another position of adjustment, a cover fitting over the casing and having slots receiving the button heads, catches on said cover insertable into the ports of the casing, a spring-urged tumbler plate movable in the casing substantially at right angles to the buttons and having on both side edges of a central aperture trapezoidal notches engageable by the bolts for being held thereby and locking said catches, and a plane 125 rocker urged by spring means into the path of the catches for holding the buttons aligned when the catches are freed from the rocker and tumbler plate while permitting selective disalignment of the buttons when the catches engage the rocker and tumbler plate.
- 130 14. A permutation lock comprising a ported casing having aligned slots, eared buttons movable along the respective slots, each button having a head projecting out of the casing, symmetrical ears and a bolt offset from its centre, the ears and bolt extending into the casing and being co-planar with the head, an indented plate adjustable from without the casing and co-operating with the button ears to retain them in one 135 position of adjustment and to release them in another position of adjustment, a cover fitting over the casing and having slots receiving the button heads, catches on said cover insertable into the ports of the casing, a spring-urged tumbler plate movable in the casing substantially at right angles to the buttons and having on both side edges of a central aperture trapezoidal notches engageable by the bolts for being held thereby and locking said catches, and a plane rocker urged by spring means into the path of the catches for holding the buttons aligned when the catches are freed from the rocker and tumbler plate while permitting selective disalignment of the buttons when the catches engage the rocker and tumbler plate.
